Primary Examiner — Wendy L Arminio

Assistant Examiner — Maheen Khurshid

CLAIM

The ornamental design for a breast pump, as shown and described.

DESCRIPTION

FIG. 1 is a front perspective view of a breast pump design showing my new design.

FIG. 2 is a front view of a breast pump.

FIG. 3 is a rear view of a breast pump.

FIG. 4 is a right side view of a breast pump.

FIG. 5 is a left side view of a breast pump.

FIG. 6 is a bottom view of a breast pump.

FIG. 7 is a top view of a breast pump; and,

FIG. 8 is a rear perspective view of a breast pump.

Any shading is not features of the design but are utilized to illustrate the surface contours of the breast pump design in the drawings.

The broken lines depict portions of the breast pump that form no part of the claimed design.
